United States Patent Office.

EDWIN F. WHITNEY AND REUBEN JONES, OF UNION MILLS, PENNSYLVANIA.

Letters Patent No. 103,265, dated May 17, 1870.

IMPROVEMENT IN BORING-TOOL.

The Schedule referred to in these Letters Patent and making part of the same.

To all whom it may concern:

Be it known that we, EDWIN F. WHITNEY and REUBEN JONES, of Union Mills, in the county of Erie and State of Pennsylvania, have invented a new and improved Boring-Tool; and we do hereby declare that the following is a full, clear, and exact description thereof, which will enable others skilled in the art to make and use the same, reference being had to the accompanying drawing forming part of this specification.

This invention relates to a new and useful improvement in a tool or bit for boring wooden pipes for pumps or wooden tubing, for conveying water, steam, gas, or other liquid or fluid; and

It consists in a bit or boring-tool, formed from a solid piece of steel or other suitable metal, with two cutting-lips, formed as hereinbefore more fully described.

In the accompanying drawing—

Figure 1 represents a longitudinal side view of the article, showing the form or curve of the cutting-lips.

Figure 2 is a view of the end or face of the bit.

Similar letters of reference indicate corresponding parts.

A is the bit or boring-tool.

B represents the shank, which may be attached to any suitable boring-head, by means of the simple square shank C, or by means of the screw-shank D, as may be found most convenient.

E and F represent the cutting-lips. These lips are formed by drawing down the metal from the shank to a thin plate, then splitting the plate centrally parallel with the shank or line of rotation, and then turning the two parts thus made in opposite directions, and curving them as seen in fig. 1.

G G are the cutting-edges. The back edges of these lips are slightly turned toward the shank, so that the cutting-edges G G readily engage with the wood.

The points of the lips H H are curved round toward the shank, so that there are no cutting-angles, which form insures a perfectly smooth hole.

The auger or boring-head is supported on two journals, to insure a true longitudinal movement.

Having thus described our invention,

We claim as new and desire to secure by Letters Patent—

The bit or boring-tool herein described, consisting of the cutting-lips E and F, bent outward in opposite directions, and curved upward and inward at their ends, as shown, said lips being formed on a shank which is either square or screw-threaded, as and for the purpose specified.

EDWIN F. WHITNEY.
REUBEN JONES.
